UNITED STATES PATENT OFFICE.

LOUIS D. PETERS, OF JACKSON, OHIO.

SIGNAL-LANTERN.

1,389,158.

Specification of Letters Patent. Patented Aug. 30, 1921.

Application filed October 4, 1920. Serial No. 414,590.

To all whom it may concern:

Be it known that I, LOUIS D. PETERS, a citizen of the United States, residing at Jackson, in the county of Jackson and State of Ohio, have invented certain new and useful Improvements in Signal-Lanterns; and I do declare the following to be a full, clear, and exact description of the invention, such as will enable others skilled in the art to 10 which it appertains to make and use the same.

This invention relates to improvements in signal lanterns which are especially designed for use by switchmen, flagmen and track-walkers for inspecting tracks, giving signals to approaching trains and for other purposes.

The main object of the invention is to provide a lantern of the above mentioned type 20 which includes a chimney guard provided with a relatively large open space into which a pane of colored glass is placed and removably held by novel means, this construction and arrangement being advantageous in that 25 it permits the ordinary lamp with a white shade to be used as a signal lamp by simply placing the colored glass in said open space of the guard. Thus, the necessity of using a lamp with a white chimney and another 30 lamp with a red chimney is entirely overcome by my construction and arrangement which permits the same lamp to serve a double purpose.

Another object of the invention is to provide an improved lantern embodying means 35 for removably holding a piece of colored glass in position, the same also including a container for holding the piece of colored glass when the latter is out of use, this container also serving to hold a number of 40 spare pieces of colored glass, if desired.

A further object of the invention is to provide a lantern of the above mentioned type which is exceedingly simple in construction, strong, durable, effective in use, and comparatively inexpensive to manufacture.

Other objects and advantages of the invention will be apparent during the course 50 of the following description.

In the accompanying drawings, forming a part of this specification and in which like numerals are employed to designate like parts throughout the same:

Figure 1 is a side elevational view of a 55 conventional lantern embodying my improvements.

Fig. 2 is a fragmentary front elevation looking in the direction of the arrow A.

Fig. 3 is a detail section taken on the line 60 3-3 of Fig. 1.

Fig. 4 is a detail perspective view of the drawer which holds the signal glass.

In carrying out my invention, I make use of a conventional type of track-walker's 65 lantern which is provided with a chimney guard in the form of an open-work wire cage. The lantern is here designated, as a whole, by the numeral 1 and the wire cage referred to is designated by the numeral 70 2, this cage being composed of a plurality of spaced vertical wires 3 connected by ring-like members or horizontal upper and lower spaced wires 4. This cage, as before indicated, is provided at one side with a relatively large open space 5 which is formed by removing a portion of the upper ring 4 between two of the vertical wires which bound 75 said space 5. At this point I wish to mention that the ordinary white shade or globe 80 will be used with this lantern so that a track-walker may inspect track conditions and effectively use it for other purposes. With my idea, the lamp may be easily and readily converted into a signal lamp by merely placing a piece of red or other colored glass into 85 the space 5. In the drawings, I have shown this piece of glass in the position in which it is placed and I have indicated it by the numeral 6. It may be held in position by 90 any suitable means, the means shown consisting of a horizontal cross-piece 7 which is connected to the vertical wires bounding said space 5 and extends horizontally between them in the manner disclosed, being provided near its ends with channel portions 95 8 to form seats for the lower edge of the glass 6. The supporting means for the signal glass as shown also includes an angle bar or member 9 which is arranged in parallelism with the cross-piece 7 and is spaced above it in the manner shown. One of the flanges of this angle is notched as indicated at 10 and the depending tongue 11 of a spring latch member 12 extends downwardly 105 through this notch and in front of the piece of glass 6 to retain the latter in position.

With this construction and arrangement, it

will be seen that the glass may be readily placed in position and securely held and may be easily and quickly removed whenever desired.

5 It is not desirable to have the signal glass fixed in position at all times, and in order to have it close at hand when desired to quickly place it in use, I provide novel means for holding it in a place which places it 10 entirely out of the way. This holder is in the form of a container or drawer 13 which is slidable in guides 14 arranged on the bottom of the burner-carrying-compartment of the lantern. To facilitate the insertion 15 and removal of the colored pieces of glass from this drawer, the front wall thereof is separated from the body portion and hingedly connected thereto and thus provides a door 15. In order to retain the 20 drawer and door in closed position, I provide an automatically acting spring-latch 16 which includes a laterally down-turned portion 17 for engaging the door 15 and retaining it in closed position and in turn 25 retaining the drawer in closed position. If desirable, this latch member may also include at its free end, a finger-piece 18 for permitting it to be readily moved to a position whereby the drawer and door may be 30 moved to a position to permit the glass to be easily and readily removed therefrom.

A lantern embodying the improvements shown in the drawings and hereinbefore clearly described is advantageous in that it 35 permits a trackwalker or switchman to carry a lamp provided with a white globe and enable him to use the same lamp for signaling purposes by simply taking one of the colored pieces of glass from the container and placing it in the relatively large open space in the cage in the manner hereinbefore set forth. The lamp may then be turned so that the rays of light shining through the colored 40 glass will be toward the engineer of an approaching train. With my construction and arrangement, the necessity of employing lanterns with white globes and lanterns with colored globes is entirely overcome 45 since a single lamp may serve the purpose of two or more lanterns as ordinarily used. Several pieces of spare colored glass may be carried in the container which I provide and the piece which has previously been in operative position on the shade guard may be 50 removed and placed within the container, in which place it is entirely out of the way.

While I have described my improved lantern as being especially adapted for use by railway employees, I wish it to be understood that it is not to be restricted to this 55 particular use, because it may be very effec-

tively used as a signal lamp on vehicles, especially horse drawn vehicles. When used on such vehicles, the lamp may be so positioned that the colored glass will be toward 65 the rear as is ordinary.

A careful consideration of the foregoing description taken in connection with the accompanying drawing will enable persons skilled in the art to which this invention 70 relates to obtain a clear understanding of the same, therefore, a more lengthy description is deemed unnecessary.

Since possibly the best results may be obtained from the construction and arrangement shown, this construction and arrangement is taken as the preferred embodiment 75 of my invention. However, I wish it to be understood that various minor changes in the shape, size, and arrangement of parts 80 may be resorted to without departing from the spirit of the invention, or the scope of the subjoined claims.

I claim:

1. In combination, a lantern provided 85 with a chimney guard in the form of an open-work wire cage having a relatively large space in one side, the wires of said cage being disposed horizontally and vertically and spaced from one another, a cross- 90 piece carrying spaced channel seats, said cross-piece being disposed horizontally between and connected to the vertical wires and bounding the lower side of said open space, and an angle-iron spaced above and arranged 95 in parallelism with the aforesaid cross-piece, being disposed between the same vertical wires at the upper side of said space, a piece of colored glass arranged in the aforesaid open space, having its lower edge resting in 100 said seats, its upper end coacting with said angle-iron, the horizontal flange of the latter being notched intermediate its ends, and a spring retainer for the glass carried by said horizontal flange, including a tongue depending through said notch and extending 105 in front of said glass to hold the latter in place.

2. The combination with a lantern, an inverted rectangular box-like member secured 110 on the bottom of the latter, having the edges of its longitudinal side walls laterally in-turned to form guide ledges, a drawer slidably mounted on said ledges, the front wall of the drawer being hinged and serving as 115 a handle, and a latch to retain the hinged wall in vertical closing position and also to hold the drawer closed.

In testimony whereof I have hereunto set my hand.

LOUIS D. PETERS.
